UNITED STATES PATENT OFFICE.

CHRIS FREEMAN, OF BLAINE, WASHINGTON.

RAINPROOF GARMENT.

Application filed October 22, 1921. Serial No. 509,546.

To all whom it may concern:

Be it known that CHRIS FREEMAN, a subject of the King of England, residing at Blaine, in the county of Whatcom and State 5 of Washington, has invented new and useful Improvements in Rainproof Garments, of which the following is a specification.

The object of the invention is to provide a simple and convenient rain proof working 10 garment suitable for use by mechanics, fishermen, sailors and others as a substitute for the comparatively awkward and bundlesome slickers ordinarily employed and yet capable of effectively excluding rain 15 and wind and leaving the wearer unhampered and free as to movements; and with this object in view the invention consists in a construction and combination of parts of which a preferred embodiment is shown 20 in the accompanying drawings, wherein:—

Figure 1 is a general view of a garment constructed in accordance with the invention.

Figure 2 is a vertical sectional view of 25 the same on the plane indicated by the line 2—2 of Figure 1.

Figure 3 is a rear view partly broken away and showing in dotted lines the arrangement of the suspender elements.

30 Figure 4 is a perspective view of the neck portion showing the overlapping edges and fastening means therefor.

Figure 5 is a perspective view showing the bellows or accordion flap for the side 35 placket.

The garment which is of one piece form or construction consists essentially of the body portion 10 and the trousers portion 11 which are separated only at the rear on a 40 waist line 12 over which the body section or member is extended to form an overhanging flap 13, and the movable or displaceable rear fold 14 of which the upper edge is free and is adapted to be supported beneath the 45 overhanging flap 13 by suspender elements 15. The trousers adjacent their points of connection to the body portion of the garment are provided with the bellows or accordion placket closing elements 16 designed 50 to permit freedom of movement of the back fold while normally occupying a folded position to permit of the arrangement of the edges of the placket in fastened relation as by 17' or the equivalent thereof.

55 The suspender element consists of the shoulder straps 15^a extending from the

shoulders of the garment to a point of intersection at 15^b and stitched to the body or waist portion of the garment, together with elastic or extensible tabs 15^c extending from the intersection of the straps and adapted to be secured by buttons or like fasteners to the upper edge of the rear displaceable fold of the trousers member of the garment.

The front of the garment is open throughout the body portion of the trousers member and the waist member with the overlapping edges thereof provided with fastening means 17 of any suitable form while the joint thus formed is further protected by a 60 storm flap 18 designed to extend exteriorly over the joint and be held in place by fastening means 19, consisting of either buttons, snaps or any preferred equivalent thereof.

Obviously the wrist and ankle portions of the arm and leg members of the garment may be provided with means for contracting them and thereby excluding moisture or may be left free according to the specific 65 use to which the garment is to be applied, any well known means for this purpose being applicable and forming no essential part of the present invention. In the same way the neck portion 19 may be closed by 70 an extension of the means employed in connection with the front of the garment to provide for a tight fit around the throat of the wearer to exclude moisture at that point.

From the above description it will be obvious that as the garment is provided with independent leg and arm members and a one piece construction of the waist and trousers, having only the front opening protected by a storm flap and the rear opening 75 protected by an overhanging flap of the waist or body, the access of rain or wind to the interior of the garment is precluded, and by the use of well known means for contracting the ankle and wrist portions of the 80 leg and arm elements it may even be possible for wading in water without exposing the wearer to contact therewith, in the event that the feet as in the ordinary practice are suitably protected by rubber boots or the like.

Having described the invention, what is claimed as new and useful is:—

A rain-proof garment of one piece construction consisting of connected body and trousers members of which the latter is 85 connected from the former at the back on a transverse waist line, the lower end of the 90

back of the body member extending exteriorly below the waist line to provide a protective flap, the trousers members being provided adjacent its points of connection to the body member with accordion placket closing elements covered by the protective flap of said body member, fasteners carried on said flap on opposite sides of said

placket closing elements, and corresponding fasteners disposed on the trousers member 10 on opposite sides of said placket closing elements for engagement with the first said fasteners for the purpose specified.

In testimony whereof he affixes signature.

CHRIS FREEMAN.
